(57) **CLAIM**

The ornamental design for an action camera mount, as shown and described.

DESCRIPTION

FIG. 1 is an isometric view of an action camera mount, which embodies my design;

FIG. 2 is a top plan view thereof;

FIG. 3 is a bottom plan view thereof;

FIG. 4 is a front side view thereof, the back side view being a mirror image thereof;

FIG. 5 is a left side view thereof, the right side view being a mirror image thereof; and,

FIG. 6 is an elevational side view thereof, rotated 45 degrees from the front side.
